[57] CLAIM

The ornamental design for a two-headed shower, as shown and described.

DESCRIPTION

FIG. 1 is a front elevational view of a two-headed shower showing my new design;

FIG. 2 is a rear elevational view thereof;

FIG. 3 is a left side elevational view thereof;

FIG. 4 is a right side elevational view thereof;

FIG. 5 is a top plan view thereof, and,

FIG. 6 is a bottom plan view thereof.

The textured pattern of the nozzles in FIG. 1 is shown partially for ease of illustration.
